4 Claims. (Cl. 197—82)

1

The present invention relates to a typewriter comprising a carriage subjected to the action of a spring and having a rack engaging with a pinion pivoted in an element secured to the framework of the machine. In these typewriters the step by step feed of the carriage during typing is effected by means of a retaining pawl and a release pawl co-operating with one or two ratchet wheels secured rigidly to the shaft of the pinion gearing with the rack of the carriage. Various manufacturers have endeavoured, without much success, to make this escapement device noiseless. In fact, for obtaining a satisfactory operation of the machine, it is necessary for the support of the pinion to be secured very rigidly to the framework of the machine. But the spring acting on the carriage is generally very strong so as to be capable of rapidly accelerating the carriage which in general is of relatively considerable weight. As a result when the accelerated movement of the carriage is stopped by the retaining pawl coming into engagement with one of the teeth of the ratchet wheel, a shock is produced which is distributed throughout the framework of the typewriter. In view of the violence of the shock and as this is repeated with the frequency of typing it will be seen that for ensuring a satisfactory operation of the machine, it is absolutely necessary to avoid any movement of the support of the pinion, in other words, it is necessary to provide a very rigid securing of the support to the framework. But in order to prevent transmission to the framework of the vibrations resultant upon the shocks and for absorbing these and reducing the noise, the simplest and most efficacious method is to provide elements of pliant material so located that there exists no path or metallic connection between the support and the framework, a requirement which appears to exclude the possibility of securing the support rigidly to the framework of the typewriter.

The present invention tends to produce a typewriter of the type above referred to and of which the support for the pinion is secured rigidly to the framework whilst avoiding a metallic path between the said support and the framework. For this purpose the machine is provided with a pinion pivoted in a removable support held rigidly in position on the framework by tightening members applying to the said support thrusts distributed on opposite sides of a plane passing through the axis of rotation of the pinion and directed at an angle relatively to the said plane.

A partial view with parts broken away of one form of construction of the machine forming the

2

subject of the invention is shown by way of example in the accompanying drawing.

According to the accompanying drawing the typewriter is provided with a framework to which are secured the various elements and members of the machine. The framework carries a carriage 2 provided with a platen 3. The carriage slides relatively to the framework of the machine and it is subjected to the action of a spring (not shown) tending to hold the said carriage in its extreme left hand position defined by the engagement of two stops (not shown) of which one is secured to the framework of the machine and the other to the carriage. The latter also carries a rack 7 with which gears a pinion 8 secured to a shaft 9 rotating in bearings (not shown) provided in a support 12. The shaft 9 also carries an escapement wheel 13 co-operating with a retaining pawl 14 and a release pawl 15. The pawls 14 and 15 are secured to an arm 17 pivoted on the said support 12 and are actuated by an actuating member 18 moved by the keys of the keyboard during typing.

The support 12 is removable and is secured rigidly to an element 20 of the framework by means of a tightening device enabling members of resilient material to be interposed between the said support 12 and the element 20 and between the tightening members and the support 12, whilst ensuring a rigid securing of the support on the said element of the framework.

The term "rigid securing" here implies a securing which prevents any movements of the support 12 having an amplitude which may be deleterious to the satisfactory operation of the typewriter.

The tightening device is provided with two flaps 21 hinged to the element 20 by two spindles 22 parallel to the shaft 9 of the pinion 8. The flaps are connected together at their free ends by a rod 23 screw-threaded at its two ends. Nuts 24 and lock-nuts 25 engaging with these screw-threaded ends, enable the flaps to bear against the support 12. The latter is provided with two bearing surfaces 26 against which the flaps 21 bear through the medium of members 27 of pliant and resilient material. Between the lower surface or bottom surface 28 of the support 12 and the element 20 are interposed members 29 of pliant and resilient material.

The operation of the typewriter described is in all respects similar to that of known machines, but it is to be observed that there is no metallic connection between the support 12 and the framework of the machine. In fact the mem-

bers 27 and 29 interrupt the mechanical connections which may exist between the support 12 and the element 20 on the one hand and between the support 12 and the tightening members for the latter on the other hand. By reason of the arrangement adopted in which the tightening members apply to the support 12 thrusts which are distributed on opposite sides of a plane perpendicular to the element 20 and passing through the axis of rotation of the pinion 8 on the one hand and on the other hand directed obliquely relatively to this plane and in the direction of the element 20, the securing of the removable support 12 is very rigid. In particular, no movement of the support 12 relatively to the element 20 is to be feared in the direction of the shocks and knocks to which it is subjected during the stopping of the escapement wheel on the retaining pawl. These knocks apply thrusts which are directed approximately parallel to the movement of the carriage, that is to say perpendicularly to the axis of the pinion 8. The bearing surfaces 26 each form an angle with the base surface 28 of the support, so that the ends of the flaps are closer together than their hinge points on the element 20. In this manner a movement of the support perpendicular to the shaft 8 is rendered impossible.

The rod 23 passes through the support through an opening 30 provided therein. This opening is of sufficient dimensions to avoid any possibility of contact between this rod and the mass of the support 12.

On examination of the drawing it will be seen readily that the vibrations generated in the support during the operation of the escapement cannot be transmitted to the framework, so that the surface of the parts in vibration is reduced to the sum of the surfaces of the support. As this surface is very small relatively to that of the framework, it is clear that the sound vibrations are practically no longer transmitted to the air and that the machine is rendered noiseless.

One form of construction of the machine forming the subject of the invention has been described herein by way of example and with reference to the drawing but it will be understood that all the elements and members described may be replaced directly by their equivalents. However, the machine described has the advantage of being provided with a removable support 12 on which are mounted all the members of the escapement device. The plac-

ing in position and withdrawal of the removable support 12 are very easy and rapid operations. In fact for placing the support in position, the support being provided with all the members of the escapement device, it suffices to place it on the framework, the members 29 being previously placed on the element 20, and then to lower the two flaps, positioning the rod 23 and tightening and locking the nuts 24. The support automatically assumes its exact longitudinal position and no mechanical connections with the actuating members of the escapement device have to be established, the part 16 of the arm carrying the retaining and escapement pawls being located automatically relatively to its actuating member.

I claim:

1. In a typewriter, the combination with a framework and a spring actuated carriage slideable on the framework, of a rack on said carriage, a pinion meshing with said rack, a support mounting said pinion for rotation, means each pivotally mounted on said framework and each clampingly engaging one of the opposite sides of said support on one side of a vertical plane passing through the axis of said pinion, means of pliant and resilient material interposed between said framework and said support, and means forcing the first means toward one another to clamp the support.

2. The combination according to claim 1, wherein the support includes a pair of bearing surfaces one on either side of said plane and each of the first means engages one of said bearing surfaces.

3. The combination according to claim 1, wherein the last mentioned means includes a rod free of the support and engaging the first means.

4. The combination according to claim 3, wherein the support has an opening and the rod extends through the opening.

O. AEBI.
